UNITED STATES PATENT OFFICE

WILFRID J. ROY, OF NEWARK, NEW JERSEY, ASSIGNOR TO GEMEX COMPANY, OF NEWARK, NEW JERSEY, A CORPORATION OF NEW JERSEY

END HOOK

Application filed May 23, 1929. Serial No. 365,370.

This invention relates to an end hook for securing a watch strap to the bail or lug of a wrist watch; and has for its object to provide a releasable connection by which the strap 5 may be secured to the end hook and held secured thereto.

A further object of the invention is to secure the clamping member of the end hook in strap securing position against accidental 10 detachment.

A still further object of the invention is the provision of detents on resilient side walls of the body portion of the end hook to snap over the edges of an L-shaped clamping member and prevent the same from accidentally 15 moving from secured position, in order that the strap member may be securely held in engagement with the end hook.

With these and other objects in view, the 20 invention consists of certain novel features of construction, as will be more fully described, and particularly pointed out in the appended claim.

In the accompanying drawings:

25 Figure 1 is a perspective view of the end hook looking at the top thereof.

Figure 2 is a perspective view of the end hook looking at the under side thereof.

Figure 3 is a section on line 3—3 of Figure 30 1.

Figure 4 is a section on line 4—4 of Figure 3, illustrating the detents as being formed from the side walls and extending over the edges of the clamping member.

35 Figure 5 is a sectional view showing the clamping member in release position.

In the use of watch strap end hooks for securing a strap to a watch, it is desirable to provide some means by which the strap may

40 be so attached to the end hook that it may be disconnected therefrom and shortened by severing an end portion and then replaced in the end hook; and in order to accomplish this result I have provided a cam acting L-shaped 45 lever clamping member pivoted between the resilient side walls in the body of the hook whereby when swung about its pivot from a released position to a gripping position the strap may be secured between the edge of the 50 clamping member and the body of the hook

to hold the same securely in position; and in order that the clamp member may not be released accidentally, I have provided detents extending inwardly from each of the resilient side walls to snap over the edges of the clamp and prevent the same from being moved to released position except by the application of a greater amount of force than would be present during working operation of the device to move the clamp about its pivoting trunnions; and the following is a detailed description of the present embodiment of this invention illustrating the preferred means by which these advantageous results may be accomplished:

With reference to the drawings, 10 designates the body of the end hook, the top being illustrated in Figure 1 from which a shank 11 extends which is bent into a U or hook form 12 and adapted to be attached to a wrist watch bail or between a pair of lugs as the case may be. It is, of course, understood that the U or hook portion 12 if closed to a greater extent than that illustrated in Figure 1, will be in the form of an eye to receive the pin 75 thru it as is common on wrist watches in use at the present time and the width of the hook portion 12 may be varied to fit different widths of lugs extending from wrist watches for attachment purposes.

The body portion is also formed with resilient side walls 13 and 14 bent from the sheet metal top portion 15 as will be clearly apparent from Figure 2, suitable bearings are formed by openings 16 in each of the side 85 walls to pivotally support an L-shaped clamping member 17 by means of its trunnions 18 extending from each side thereof into the bearing openings 16 in the side walls by which the clamping member may swing to cause its portion 19 on one side of its pivoting trunnions 18 to be parallel with the top wall 15 when desired as illustrated on Figure 5 to provide an entering opening for the strap, after which it may be swung to its clamping position, as illustrated in Figure 3, so that the strap 20 will be positioned between the serrated edge 21 of the portion 19 and the top 95 15 of the body of the hook to secure it thereto.

In moving the clamping member to secur-

ing position, the lever portion 22 of the clamping member snaps over the detents 23 which extend inwardly toward each other from the resilient side walls 13 and 14, it being understood that there is sufficient resiliency of these side walls to permit them to spread as the clamping lever engages the rounded surface of the detents 23 and is manually forced thereby in being moved to the clamping position illustrated in Figure 3. A notch 24 is provided in the edge of the lever portion of the clamping member to assist in lifting it from clamping position when desired.

By the construction here illustrated and described it will be apparent that the clamping member may be swung to such position as to allow unobstructed entry of the strap into the body of the hook or a withdrawal of the strap from such position when desired to be severed for adjustment of the encircling length about the wrist and then replaced between the clamping member and the body portion of the hook for securing the same in position.

The clamping member has teeth on its gripping portion 19 to bite into the strap and its handle portion 22 extends at right angles to this gripping portion as shown in Fig. 3. When in gripping position the end of the handle portion 22 lies in contact with the body and at an angle thereto, in order to be below the detents 23 and as the teeth are imbedded in the strap any movement of the strap will cause the gripping portion 19 to further grip the strap by the teeth moving therewith and such action of the lever will also be against the pressure of the detents 23.

The foregoing description is directed solely towards the construction illustrated, but I desire it to be understood that I reserve the privilege of resorting to all the mechanical changes to which the device is susceptible, the invention being defined and limited only by the terms of the appended claim.

I claim:

A watch bracelet end hook comprising a sheet metal body, side walls on said body having aligned openings, a shank extending from said body with a watch engaging hook end, an L-shaped clamp lever having right angularly extending gripping and handle portions, said handle portion being flat throughout its length and provided at the junction of said portions with lateral extensions pivotally mounted in said aligned openings, and adapted to secure a strap to the hook when in gripping position, and inwardly projecting detents on said side walls beneath which the handle portion of said lever may be forced when moved at an angle to said body to releasably retain said lever in gripping position, the entire space between said walls below said detents being unobstructed to permit the lever to engage the shank, said gripping portion having teeth to extend into the strap, whereby said lever is moved about its pivot into firmer

gripping position against the action of said detents upon detaching movement of the strap when the lever is in gripping position.

In testimony whereof I affix my signature.

WILFRID J. ROY.
